(57) **CLAIM**

The ornamental design for an orchid goblet planter, as shown and described.

DESCRIPTION

FIG. 1 is a perspective view of the orchid goblet planter, showing the design;

FIG. 2 is a front perspective view thereof;

FIG. 3 is a rear perspective view thereof;

FIG. 4 is a left side perspective view thereof;

FIG. 5 is a right side perspective view thereof;

FIG. 6 is a top perspective view thereof; and,

FIG. 7 is a bottom perspective view thereof.

The broken lines represent portions of the orchid goblet planter and form no part of the claimed design.
